UNITED STATES PATENT OFFICE.

SAMUEL K. DENNIS, OF CHICAGO, ILLINOIS, ASSIGNOR TO THE PLANO MANUFACTURING COMPANY, OF SAME PLACE.

DESIGN FOR A STATIONARY JAW FOR TYING-BILLS.

SPECIFICATION forming part of Design No. 33,190, dated September 11, 1900.

Application filed August 4, 1900. Serial No. 25,948. Term of patent 14 years.

To all whom it may concern:

Be it known that I, SAMUEL K. DENNIS, a citizen of the United States, residing at Chicago, in the county of Cook and State of Illinois, have invented and produced a new and useful Design for a Stationary Jaw for Tying Bills, of which the following is a specification.

Figure 1 is a side elevation of my improved jaw. Fig. 2 is a side elevation of the opposite side. Fig. 3 is a front elevation with a portion of the stem broken away. Fig. 4 is a rear elevation. Fig. 5 is a top plan view, and Fig. 6 is a bottom plan view.

As shown in the drawings, the essential features of my design are the cylindrical stem *a*, terminating in the shoulder, which around the rear side forms the narrow semicircular horizontal shelf or flange *b*, while around the front side it forms the substantially crescent-shaped flange *c* in continuation of the flange *b*. The jaw proper is a hook-shaped piece *d*, which tapers slightly from the tip *e* to the point *f*, where the horizontal portion terminates. From this point *f* it is turned upward and flares rapidly toward the front and the

side, (shown in Fig. 1,) its front edge forming the flange *c*, while its side edge forms the downwardly-curved flange *g*. The lower rear end of the flange *g* runs into the heel portion *h*, which has the rectangular channel *j* cut through it and the body of the jaw. The rivet-hole *k*, passing through the body of the jaw, intersects the channel *j* at right angles. The continuation of the channel *j* forms the groove *l* in the upper side of the jaw. The heel portion *h* does not extend so far up as the top of the flange *b*, so that a semicircular shoulder *m* is formed between the flange *b* and the heel portion *h*.

Having described my invention, what I claim as new, and desire to secure by Letters Patent, is—

The design for a stationary jaw for tying-bills substantially as herein shown and described.

SAMUEL K. DENNIS.
